UNITED STATES PATENT OFFICE.

EDWARD H. PHIPPS, OF NEW YORK, N. Y., ASSIGNOR TO PHIPPS ROAD CAR COMPANY, OF JERSEY CITY, NEW JERSEY, A CORPORATION OF NEW JERSEY.

DESIGN FOR A VEHICLE-BODY.

SPECIFICATION forming part of Design No. 36,138, dated November 11, 1902.

Application filed July 3, 1902. Serial No. 114,325. Term of patent 14 years.

To all whom it may concern:

Be it known that I, EDWARD H. PHIPPS, a citizen of the United States, residing at New York, in the county of Kings and State of New York, have invented a new, original, and ornamental Design for Vehicle - Bodies, of which the following is a specification, reference being had to the accompanying drawings, forming part thereof.

Figure 1 is a side elevation of the vehicle-body, showing my new design. Fig. 2 is a plan view of the vehicle-body, and Fig. 3 is a rear end view thereof.

As shown in the drawings, the leading or material feature of my design is the body proper, having the molded or beaded lower portion, the tapering or inclined ends, and the transverse open section near the center.

The body has its lower edge portion 10 molded or beaded, as shown, and extending transversely across the body near the center is the opening 11.

The body is of a substantially uniform width, but has its end portions inclined or 25 tapered, as shown at 12, and these inclined

parts are paneled, as at 13. The steps 14 are dropped below the carriage-bottom, and when viewed in end elevation the steps stand off from the body, as shown in Fig. 3. They are supported by the hangers or braces 16 and 30 the end rods 15, which latter are arranged on opposite sides of the opening 11 and extend upward to the upper part of the body.

The body is flat on the top, and at the sides has the guard-rails 17. The seat 18 is rounded 35 at the rear corners, and when the carriage-body is viewed in end elevation the seat juts out over the sides of the body.

Having described my invention, what I claim as new, and desire to secure by Letters 40 Patent, is—

The ornamental design for vehicle - body herein shown and described.

In testimony whereof I have signed my name to this specification in the presence of 45 two subscribing witnesses.

EDWARD H. PHIPPS.
